UNITED STATES PATENT OFFICE

2,014,613

APPARATUS FOR RAISING FLUIDS

John J. Ceverha, Chicago, Ill.

Application December 12, 1934, Serial No. 757,119

2 Claims. (Cl. 103—44)

My invention relates in general to apparatus for raising fluids from one level to a higher predetermined level and, more particularly, to one in which balanced columns of fluid are utilized 3 as a means to assist each other to surge alternately upwards and downward in opposed motion.

The object of my invention is to provide an apparatus to raise fluids great heights with a 10 minimum of effort.

A further object is to provide a simple and easily installed apparatus which, owing to its comparatively effortless operation, needs no heavy machinery, such as powerful engines, etc., for 15 the successful operation with a consequent reduction in cost and operating expenses.

The various features of novelty whereby my invention is characterized will hereinafter be pointed out with particularity in the claims; 20 but, for a full understanding of my invention and of its objects and advantages, reference may be had to the following detailed description taken in connection with the accompanying drawing, wherein:

Figure 1 is an elevation, partly in section, showing one form of my improved apparatus; Fig. 2 shows a slightly modified arrangement of some of the parts shown in Fig. 1; Fig. 3 shows another modified form which is the same in action 25 and principle as Figs. 1 and 2.

Referring to the drawing, and especially Fig. 1, 1 represents a perforated pipe, the lower end of which rests on the bottom of a well or other source of supply in which it is placed and acts as a support for the rest of my apparatus. This tube is closed at its upper end by a downwardly-seating check valve 2 in the lowermost end of a casting comprising bores or passages 3, 4, 5 and 6. Lengths of pipe or tubing 7 and 8, threadedly 30 or otherwise secured in the upper ends of the bores 4 and 6, respectively, form long, continuous, vertical channels to any predetermined height as, for instance, the ground level, if the apparatus is operating in an oil well. I provide horizontal extensions 9 and 10 of the tubes 7 and 8, and in the extension 9 which is the discharge line, as will be hereinafter more fully described, is a check valve 11 which permits the 35 passage of fluids or the like in the direction of the arrow. A goose neck 12, sealed at its upper end, is provided near the upper end of the tube 7. The open end of the tube 10 is closed by an elbow 13 in which is threadedly, or otherwise, secured, a short vertical tube 14. In the tube 10,

intermediate its ends, is a double-acting piston 15 secured to a piston rod 16. This piston rod is guided in a packing gland 17 formed on the elbow 13 and is connected with a connecting rod 18, which in turn connects with a crank 19 on the shaft 20 of a motor or other source of power 21.

Referring to the casting and the various passages therein, it will be seen that the bores or passages 3 and 5 are separated by a wall 22 having a boss in which a piston rod 23, connecting pistons 24 and 25, is guided.

Communication between passages 3 and 4 is made immediately below the wall 22, while communication between passages 4 and 5 is made adjacent the upper end of the passage 4, and communication between passages 5 and 6 is made immediately above the said wall 22. Assuming that the apparatus has been fully primed with fluid through the priming openings in 9 and 10, the casting, pipes 7 and 8, horizontal extensions 9 and 10, as well as goose neck 12, completely filled, all air having been expelled therefrom, it will be seen that I have provided a column of fluid in the tube 8, the entire weight of which is exerted against the under side of the double-acting piston 24 in the passage 5, intermediate the junctures therewith of the passages 4 and 6.

The weight of the column of fluid in the tube 7 is distributed in approximately equal ratio to the 30 passages 3 and 5. Therefore, half, or approximately half, of the load is exerted on the top of piston 24 while the remaining portion of the load is exerted above the piston 25. This distribution of the load, one-half of the weight of which exerting a downward force above one piston, the other half exerting a like force above the other, while the total weight of the fluid in the other tube exerts a concentrated force below one of the pistons equal to that exerted above the two 40 pistons. Thus, an approximate balance of the two columns is established above and below the pistons which causes them to practically float. To provide an air seal for piston 15, the extension 10 is filled with oil or other fluid until it reaches 45 a level in the tube 14, which is open at the upper end, only sufficiently high to provide space for the surge of fluid displaced by the movement of reciprocating piston 15.

It will be readily seen that, owing to the balance of weight in the two columns, it will require very little effort to cause one column to rise and the other to fall. Hence, a very small motor may be used to reciprocate the piston 15. This reciprocation, say, for instance, first to the right, as 50 55

viewed in the drawing, will raise the fluid in tube 8 and passage 6 and draw the fluid in passage 5 below piston 24 downwardly, which permits the fluid in tube 7 and passage 4 to follow and assist the fluid in the other column in its upward movement. The fluid displaced in tube 7 is replenished from the goose neck 12, owing to the flow in the discharge pipe 9 being checked in this direction by check valve 11 which prevents surge in discharge line.

As pistons 24 and 25 fall, a quantity of fluid trapped in the passage 3 between the piston 25 and check valve 2 will pass said piston and, as the movement of the fluid in the two columns is reversed by the reciprocation of piston 15 in the opposite direction, the fluid above the piston 25 will be raised thereby. The fluid taken from the goose neck 12 during the down surge will be replaced therein, and the surplus raised in passage 3 will be forced past the valve 11 into the discharge line. Owing to the slight effort required to effect these results, the piston 15 may be rapidly reciprocated to cause a continuous flow in the discharge line.

Referring to Fig. 2, 30 is a conduit separated from a similar conduit 31 by a partition wall 32 immediately above which communication is made between the conduit 31 and a conduit 33. A by-pass 34 connects conduits 30 and 31. Pistons identical with those described in my preferred form of apparatus are situated in the conduits 30 and 31. The operation of this form is exactly the same as that previously described.

Referring to Fig. 3, 40 represents a conduit separated from a conduit 41 by a partition wall 42. A sleeve 43 surrounding conduits 40 and 41 and spaced therefrom provides a by-pass to connect said conduits through ports 44 and 45. A

third conduit 46 communicates with conduit 41 immediately above the partition wall 42. It will not be necessary to describe the operation of this form in detail as it is identical with those previously described. The sleeve 43 merely replaces the passage 4 described in the first form shown in Fig. 1 of the drawing.

I claim:

1. In an apparatus of the character described, means for maintaining fluids in balanced columns, a pulsator to shift said columns in opposite directions simultaneously, a piston disposed to receive the balanced weight of the columns on opposite sides thereof and float freely with the fluid as it is moved in first one direction and then the opposite, a by-pass, a pump plunger or piston arranged in said by-pass and connected to and operated by said floating piston, and a check valve positioned in the by-pass below said pump plunger.

2. Substantially parallel vertical conduits provided at their uppermost extremities with horizontal extensions, a piston in one of said extensions, and a motor or other source of power to reciprocate said piston, a check valve in the other horizontal or discharge extension, a reservoir at or near the uppermost end of the vertical discharge conduit, an intake conduit, a by-pass connecting the discharge conduit with said intake conduit, connected pistons so disposed in the conduits as to be balanced by the equal distribution of the weight, both above and below, of the contents of the vertical conduits and by-pass, and a check valve so disposed in this intake or supply conduit as to prevent the return of fluids or the like which have entered said conduit from the source of supply.

JOHN J. CEVERHA.
